(57) **CLAIM**

I claim the ornamental design for a gaming chip case, as shown and described.

DESCRIPTION

FIG. 1 is a top, front, left side perspective view of a gaming chip case, with the locking cover shown in the locked position, embodying my new design;

FIG. 2 is a rear, bottom, right side perspective view thereof;

FIG. 3 is a left side elevational view of FIG. 1;

FIG. 4 is a top plan view of FIG. 1;

FIG. 5 is a bottom plan view of FIG. 1;

FIG. 6 is a top, front, left side perspective view of the gaming chip case, with the locking cover shown in the unlocked position;

FIG. 7 is a rear, bottom, right side perspective view of FIG. 6;

FIG. 8 is a left side elevational view of FIG. 6;

FIG. 9 is a top plan view of FIG. 6; and,

FIG. 10 is a bottom plan view of FIG. 6.
